UNITED STATES PATENT OFFICE.

EUGEN GOTTFRIED DIHLMANN, OF LEIPZIG-REUDNITZ, GERMANY.

SHOE-PRESS.

1,276,627.

Specification of Letters Patent. Patented Aug. 20, 1918.

Application filed December 5, 1917. Serial No. 205,682.

To all whom it may concern:

Be it known that I, EUGEN GOTTFRIED DIHLMANN, a subject of the King of Wurttemberg, residing at No. 3 Palmstrasse, in the city of Leipzig-Reudnitz, in Germany, have invented new and useful Improvements in Shoe-Presses, of which the following is a specification.

This invention relates to shoe-presses used in the manufacture of boots and shoes by uniting the upper with the sole exclusively by the application of a cementing or adhesive substance, the shoe thereby being clamped between conveniently shaped parts of the press, in order to obtain a sure binding of the edges of the leather to be cemented together. The invention more especially relates to those parts of the press which directly act upon the work piece which is in the press at the time, and its object is to obtain a device adapted for an easy and quick operation of the parts thereof.

For this purpose the parts of the press which are in direct contact with the work piece or shoe are adjustable in several respects and loosely arranged, so that they can be brought in contact with a work piece out of the press and inserted and displaced therein together with said work piece.

A press of this construction presents the advantage that its operative parts may be placed upon the work piece, when removed from the press, in which case the combination of said elements is accessible from all sides, thus permitting a treatment of the work piece for the subsequent pressing operation, whereafter the united parts can be inserted into the press as a whole. Other objects and advantages will more fully appear from the following specification and be pointed out in the appended claims.

The details of the invention are illustrated in the accompanying drawings, which are to be taken as a part of this specification, and in which—

Figure 1 is a partial side elevation, representing an embodiment, of the invention, while

Fig. 2 shows a top view thereof.

Fig. 3 represents the front elevation of the head of the press.

Fig. 4 is a side elevation of a modified construction of the press.

Fig. 5 is a cross section of a detail, and

Fig. 6 shows a cross section of a further

modification of the loose yoke or bow of the press.

Similar numerals denote similar parts throughout all figures of the drawing.

Referring to Figs. 1 to 3, a cross-piece 41 having any suitable shape and being adapted to transmit the pressure of the pressing member 40 on to the shoe to be pressed, is used; it carries at one end a stay or support 42 of known construction which rests upon the fore end of the shoe or boot, and carries at its rear end a pressure piece or block 43 provided with a last-pin 44 (see Figs. 1 and 5). The said parts 42 and 43 are articulated upon the bow 41 by means of hinges 45 and 46, respectively. The support 42 is made of two parts capable of being screwed into one another, so that the length of the said support can be varied and conformed to the height of a last. The pressure block 43 is recessed with a bore receiving a helical spring 49 (Fig. 5), which tangentially bears with its upper extremity against the end-face of the bow 41 in such a manner as to have the tendency to turn the pressure block 43 with the last-pin rigidly fixed thereon, about the hinge 46 toward the support 42.

When the pressure block 43 rests upon the upper face of a last 50, the pin 44 engages the usual bore of said last, the fore end of the block 43 directed to the point of the shoe, projects or laps over the instep-block 48 of the last 50 and holds said instep-block against displacement. When the support 42 bears upon the fore end of the instep-block 48, as may be better seen in Fig. 1, owing to the inclination and curvature of the upper portion of the instep-block, the same is not likely to be moved out of its proper position, that is to say, be forced upwardly or stretched apart from the last, thereby altering the shape of the lasted upper.

The lower extremity of the screw-spindle 40 having handles 9 or the like, is guided in a sleeve 52 attached in any suitable manner to the head 53 of the press 6, 7 and provided with a vertical cross-slot 47 of corresponding width to receive the yoke part of the bow 41 which is movable therein lengthwise and may easily be withdrawn therefrom. When the spindle acts upon the bow, the latter will be displaced downwardly in the slot 47, but be prevented from lateral oscillation.

The rest or bed 55 of the sole of the shoe to be pressed may have any suitable form, 110

- i. e.*, may be a bed-plate having the average shape of the shoe and containing a liner 56 of yielding material in a recess of its upper face. A cushion having a liquid or a semi-plastic filling may however be used as a bed for the shoe, as well as a self-adjusting support 5, shown in Fig. 4, which has been fully described in my specification, Serial No. 150,853.
- 10 The beds 55 and 5, respectively, can be shifted lengthwise in unison with the bows 41 and 41' respectively, being guided with downwardly projecting pairs of feet or standards 21 and 21', respectively, on a rib 22 of a supporting-table 24, Fig. 1, or the corresponding support shown in Fig. 4. The bed plate 55 (Fig. 1) is further held on a set screw 23 provided in a supporting-table 24, and which can engage several recesses of the under side of the bed plate and is adjustable vertically, so that the bed plate 55 which is tiltable about the feet 21, may be given any desired inclination. The table 24 on its part is mounted upon a screw-bolt 25 which is received in a vertical bore of the lower arm 7 of the press and engaged in corresponding female threads of a hand wheel 26, by the rotation of which, as will be obvious, the bed plate 55 can be adjusted 30 in any required height below the head 53 in conformity with the height of the last used at the time being. This will allow of the insertion into the press, of the bed plate together with the shoe and the bow 41, 35 which latter is at the same time introduced into the guide slot 47, whereafter a small stroke of the press-member 40 will be sufficient to press the shoe upon the bed.
- 40 The press heretofore described is operated and acts as follows: The press bow 41 is applied out of the press to the work piece, that is to say, the shoe and the last therein, by engaging its pin 44 into the corresponding bore of the last and placing the support 45 42 on the fore part of the shoe, as shown in Fig. 1, when the power of the spring 49 will automatically clamp the bow on to the work piece and secure the said parts to one another, so that they may be handled as one piece. The edges of the upper and the sole may now be prepared for sticking by suitably applying the adhesive thereto; this can be done without any danger of the bow altering its position relatively to the work piece. 50 The shoe thus made ready for the pressing operation is then placed with its sole upon the bed 55 and adjusted thereon, in order to be fully in contact therewith in its entire area. The assembled parts can now be inserted into the press as a whole from the front of the press, whereby the bed is brought to engage the rib 22, while the bow enters the slot 47 and is advanced therein as far as required for the desired distribution 55 of the pressure of the spindle 40 to the fore

and rear ends of the shoe, the spindle being able to work upon any part of the back face of the bow. Generally the bed must be shifted in accordance therewith. Besides the preceding adjustment of the work piece 70 with respect to the bow and the bed, which adjustment had been made out of the press, no further displacement is necessary when placed in the press; on the contrary the sure guiding of the press-members 41 and 55 has 75 the effect to prevent the work piece from any inadvertent shifting off its proper position during pressing. Finished the sticking, the shoe together with the bow and the bed can be withdrawn out off the press in the same 80 manner and then separated from the said press members. The method presents great advantages in the manufacture, as the work pieces can be treated out of the press by one or more boys who deliver the aggregate, 85 composed of bed, work piece, and bow, to the operator of the press. It is understood, that owing to the elements of the aggregate being already in contact with one another, only a small downward stroke of the press 90 spindle 40 is required to press the shoe firmly upon the bed plate 55. Of course, the bed 55 may remain in the press, if its face exactly corresponds to the sole, so that an adjustment of the shoe thereon out of the press 95 can be dispensed with.

If a self-adjusting bed 5 is used (Fig. 4), the bearing face of which automatically conforms itself to the curvature of the sole, there is no necessity to remove it from the 100 press; it can be adjustably secured by means of a set screw 28' movable in a slot 29' of the supporting arm 7' of the press. Only the united bow and work piece are manipulated separately out of the press and put together upon the bed fast in the press. 105

The modified bow 41', shown in Fig. 4 has a stay 42' and an inclined prismatic guide 57 adapted to regulate the position of the said stay. Furthermore, the spring 49' is 110 not housed in a bore but its extremities are merely attached to the press-block 43' and the bow 41', respectively.

The fast arrangement of the bed 5 upon the press makes it desirable to dispose the 115 means for regulating the height of the stroke upon the upper arm 6'. To this end a screw threaded sleeve 20' receiving the spindle 40', is vertically movable in the head 53'. The details of such construction are well known 120 in the art. In this modification the guide 47' is connected with the screw spindle 40' and will therefore be moved up and down with it.

Fig. 6 illustrates a modification of the 125 engagement between the bow and the spindle, *i. e.*, a longitudinal groove is provided in the upper side of the bow 41" capable of receiving the reduced lower extremity of the press spindle 40".

In lieu of the spindle, any pressing device is applicable in the press, *i. e.*, a lever, an eccentric, a hydraulic press, rack and pinion, or other known means may suit the purpose.

5 It is seen from the description that the invention may be performed and embodied in different ways. I, therefore, do not wish to be limited to the constructions illustrated as examples but what I broadly claim as my 10 invention, and desire to secure by Letters Patent is—

1. In a press for the manufacture of boots and shoes, the combination, with a press device, of a loose press bow detachably engageable with said press device, means carried at one end of said bow for forcing the other end thereof into clamping relation with a work piece, means for holding the work piece up against the bow, and a guide 20 in which the press bow is longitudinally movable.

2. In a press for the manufacture of boots and shoes, the combination, with a press device, of a loose bow detachably engageable with said press device, a guide, carried by the press device, in which the bow is longitudinally slideable, means carried at one end of said bow for forcing the other end thereof into clamping relation 25 with a work-piece, and a bed for the work-piece, holding the latter up against the bow.

3. In a press for the purposes described, the combination with a press device having a guide, of a loose press bow lengthwise adjustable on said guide, said bow being capable of engagement with a work-piece out of 30 the press, and a bed for the work piece, said bed being adjustable lengthwise in unison with the bow.

40 4. A press bow of the kind and for the purposes described, having supports hinged thereto at opposite ends and adapted to bear on a work piece and means at one end co-

operating with the support at the other end for clamping the press bow onto the 45 work piece.

5. In a press for the purposes described, the combination with a press device having a guide, of a loose press bow adapted to be attached to a work piece out of the press 50 and to be engaged with the longitudinal guide of the press device, a bed for the work piece, and means for adjusting the bed together with the press bow.

6. In a press for the purposes described, 55 the combination with a press device of a loose press bow, a bed for a work piece said press bow and bed being adapted to be engaged with a work piece and introduced with it into the press as a whole guiding means 60 for the press bow and bed, and means for adjusting the bow and bed lengthwise of the press.

7. A press bow of the kind and for the purpose described, having a press block 65 hinged thereto and bearing on the upper face of the detachable instep block of a last, means at one end of the bow tending to force the other end thereof down upon the work piece, and means for holding the work piece 70 up against the bow.

8. A press bow of the kind and for the purpose described, having a press block hinged thereto at one end, a last pin, a spring arranged between the press bow and the 75 press block at one end of the bow tending to force the other end thereof down upon the work piece, and means for holding the work piece up against the bow.

In witness whereof I have affixed my signature to this specification in the presence of two subscribing witnesses.

EUGEN GOTTFRIED DIHLMANN.
